SAMUEL BLAIR MACMILLAN, OF NEW YORK, N. Y.

DOORSTOP

Application filed February 20, 1931. Serial No. 517,191.

The present invention relates to door attached stops or checks, and has for its object an improvement in that type of stop or check that acts as a door jam between the bottom of a door and the adjacent floor.

One of the objects of the present device is to provide a pivoted stop with an arcuate floor engaging member the face of which, while arcuate, is eccentric to the pivotal door mounting bracket so that a fast acting wedge action is initiated when the floor stop bracket is thrown into door stopping action.

Another feature is to provide the stop with a constant acting locking spring whereby to automatically lock the door stop in raised non-operating position, but to be active in frictioning the stop against loose motion when in action as a door stop and thereby to prevent, by the drag so provided, the door from closing by a draft of air acting in a direction opposite to the door stopping action.

These and other capabilities will be noted as the herein description proceeds and it is obvious that modifications may be made in the herein noted construction, without departing from the spirit hereof, or the scope of the appended claims.

In the drawing,

Fig. 1 is a view showing a fragment of the lower portion of a door, showing my device partly broken away to better illustrate the interior details of construction;

Fig. 2 is a similar view showing a front view similarly broken away for the same purpose;

Fig. 3 is a sectional view taken on line 3—3, Fig. 1 looking in the direction of the arrows;

Fig. 4 is a sectional view of the arcuate stop head taken on the line 4—4, Fig. 1, looking in the direction of the arrows; and

Fig. 5 is a perspective front view of the pivot plate with the pivoted stop member removed.

The device is a two piece stop, preferably of cast finished brass, done in smooth hardware finish, and comprises a door attaching pivot plate 1, Fig. 5, having countersunk holes 2 therein for attaching to a door 4

by means of wood screws 3—3 shown dotted in Fig. 1, and a pivoted stop arm 5 having an arcuate head 6 upon which is mounted a rubber stop head 7.

The stop arm 5 is yoked and bored as at 8 Fig. 1 to receive thereon the pivot pin 9, which pin is fixedly held in the yoke 10 and riveted therein and freely revolves in the bore 11 of the lug 12 on door plate 1 the bored lug being fully shown in Fig. 5.

The stop arm 5 as is shown in the broken away portion in Fig. 1, is bored longitudinally from inside the yoke portion 10 to form a bottomed seat or bore 13 for a compressed coil spring 14 to be mounted therein and a steel ball 15 is set in against the spring 14, so that in any position the ball pressed against the round nose of the pivot lug 12 on door plate 1, in any position, thus creating a constant tension between the pivoted stop arm 5 and its lug mounting 12 on plate 1. As thus constructed a constant drag is exerted on the stop arm and head in position as a stop on the floor, or in non-stopping location.

When the stop member is moved to the operative position as shown in Fig. 1 in dotted lines, the spring pressed ball tends to keep the head 6 in operative set position against the floor 16 and thus prevents the door from moving oppositely to the stopping position, unless done so by actual manual movement.

When the stop member is moved to inoperative position as shown by full lines in Fig. 1, the spring pressed ball drops into a detent depression 17 at the top of lug 12 of the door plate 1 and causes the stop member to be firmly retained against movement, except when actually moved downwardly for action.

The facing or pedal surface 20 of the arcuate stop head 6 is of some resilient material such as rubber, and is moulded so that a broad knurled-like friction surface is presented to the floor. This is affixed to the head by means of a hollow seat 21 located in said head, into which fits a moulded hollow-seat fitting lug 22 on the rear of the curved

facing 20, which lug is fitted into said hollow seat and a pin 23 is driven through transversely located bores 24—24, in the walls of said head 6, as in Fig. 4, and passes through 5 the lug 22, and thereby locks the friction face in position.

The stop head 6, as previously noted, is of curved form, as viewed from the side, as in Fig. 1. The radius of the face of 6 is not 10 truly radial from the center of pivot 9, however, but is developed from a point offset from said center. For the present purpose, by referring to the dotted outline shown in Fig. 1, the center of the radius forming the 15 curved face of the head 6 could be offset, from the pivot center of 9, and be at a point X Fig. 1, and the radius indicated by R.

Thus, in action the curved head 6 when 20 rocked on the center of pivot 9, describes an arc of movement indicated by the radius r , Fig. 1, the difference of the two being indicated by the dimension d . Thus, as the door is moved in the direction of arrow B, Fig. 1, the eccentricity of the curved stop or head 6 25 causes the door to be lifted upwardly from the floor, and thus jam the stop against the floor, firmly.

The spring 14 presses the ball at times 30 against said face 12 and into said depression 17 for holding the stop arm 5 upright flat against said plate 1.

Said arcuate stop head 6 has its inner end 35 flush with the plate-engaging face of the arm and the outer end overhangs a considerable distance from the vertical axis of the arm when upright. The wide recess forming a seat 21 has side and end walls and a wide flat bottom; and the tread portion lies over said walls.

Said overhanging part of the stop head 40 engages with the floor beneath the door stop to stop the door, thus leaving the inner end part of the head sufficiently remote from the floor (after all possible wear of the tread 45 permitted by the side walls of the recess) to receive thereunder the whole of a toe of a shoe for engaging a horizontal face of a corrugation for lifting the arm to vertical position.

Said overhanging part, when the arm is 50 vertical, projects far out from a vertical plane passing through the axis of the pivot pin, thereby to cause the arm to move easily 55 downward against the restraining action of said ball 15, when said overhanging end is pressed upon vertically downwardly.

Having thus described my invention what I claim is:

60 1. In combination, a stop arm adapted to be pivoted to the lower margin of a door for movement in a plane transverse to the door and floor; said arm being disposable in substantially upright position and provided at 65 its free end with an offset arcuate head dis-

posed substantially in said plane with its inner end substantially flush with the back of said arm and its outer end overhanging a considerable distance from the vertical radial axis of the arm when upright; means for yieldably holding said arm in upright position; the outer peripheral face of said head being provided with an arcuate friction tread; said overhanging part, when the arm is in vertical position projecting far out from a vertical plane passing through the pivotal axis of the arm, thereby to cause the arm to move down against the restraining action of said yieldable means, when said overhanging end is pressed upon vertically downwardly.

2. In combination, a pivot member adapted to be attached to the lower margin of a door; a stop arm having a yoked inner end pivotally embracing said lug; means for yieldably holding the stop arm in upright position; said arm being provided at its free end with an arcuate head having its outer end overhanging a considerable distance from the vertical axis of the arm when upright, the peripheral face of said head having a tread portion thereon, having transverse corrugations; said overhanging part, when the arm is vertical, projecting far out from a vertical plane passing through the pivotal axis of the arm, thereby to cause the arm to move down against the restraining action of said yieldable means when said corrugations of said overhanging end are pressed upon vertically downwardly.

3. In combination, a pivot member adapted to be secured to the lower margin of a door; a stop arm pivoted to said member for movement in a plane substantially perpendicular to the door and floor; yieldable means for yieldably holding the arm in upright position; said arm being provided at its free end with an arcuate head disposed in said plane; the outer peripheral face of said head being formed with a wide recess forming a seat having side walls; a yieldable tread block fitting in said seat and on said walls and having transverse corrugations; the peripheral faces of said side walls and tread portion being disposed on the arc of a circle differing from an arc of a circle having its center on said pivot member when the arm is directed downwardly, the inner end part of said faces being less remote from the pivot member than the outer end part of said faces; said inner end part being engageable with the floor near the door to stop the door, the head being curved to leave the outer end part of the head sufficiently remote from the floor, after all possible wear of the tread permitted by the side walls, to receive thereunder the toe of a shoe for lifting vertically against the horizontal faces of the corrugations, for lifting the arm to vertical position.

4. In combination, a vertically elongated

5 pivot plate adapted to be attached to the lower part of a door, and having a pivot lug at the lower end of its outer face; said lug having a partly cylindrical outer and lower
10 face, a depression in its top face and a transverse bore; a stop arm having a yoked inner end embracing said lug and a pivot pin transverse to said end and engaged in said bore; said arm having a longitudinal bore having a closed interior end, and an open end adjacent to said lug; a ball and a spring in the bore, the spring pressing the ball at times against said face, and into said depression for holding the stop arm upright flat against
15 said plate; said arm being provided at its outer end with an arcuate head having its

inner end flush with the plate-engaging face of the arm and the outer end overhanging a considerable distance from the vertical axis of the arm when upright; said arm being swingable downwardly and having a friction tread portion secured to the outer peripheral face of said head for engaging a floor in stopping position, the peripheral face of said tread portion being disposed, when in said position, on the arc of a circle having its outer end more remote from said pin than its inner end, whereby to increase the stopping effect.

Signed at Brooklyn in the county of Kings and State of New York this 7th day of February A. D. 1931.

SAMUEL BLAIR MACMILLAN.
